EARRING CONSTRUCTION

James Conto and Benjamin Alstadt,
New York, N. Y.

Application July 28, 1948, Serial No. 41,045

8 Claims. (Cl. 63—14)

1

The invention relates to an earring construction wherein decorative ear ornaments of different designs and shapes may be detachably secured to an ear clasping means.

The main object of the invention is to provide an earring comprised of separable members, one of which is an ear ornament having a fixed eye on the underface thereof, and the other, an ear clasping device having means associated therewith adapted to be detachably engaged by said eye and means for resiliently holding the ornament in position with respect thereto when said eye is engaged by said engaging means.

A further object is to provide an earring construction comprised of separable members one of which is an ear ornament having a decorative outer face and an inner face having a fixed eye member mounted thereon, and the other an ear clasping device provided with means for detachably engaging said eye, and a coiled spring for resiliently holding the ear ornament in position with respect thereto.

A further object is to provide an earring construction comprised of an ear ornament consisting of a decorative button having a fixed eye member on its under face, and an ear clasping device provided with means for engaging said eye member and with spring means for resiliently holding the button ornament in position with respect thereto.

A further object is to provide a novel construction of an ear clasping means for an earring ornament and which is provided with means for detachably and resiliently holding an ear ornament with respect thereto.

A practical embodiment of the invention is shown in the accompanying drawing and in which similar characters of reference indicate corresponding parts in the several views.

Referring to the drawings—

Figure 1 is a side elevational view of an earring construction embodying the features of the invention and showing the same in its assembled form;

Figure 2 is a cross-sectional view of the parts of the construction shown in disassembled relation;

Figure 3 is a side elevational sectional view of the earring construction in its assembled form;

Figure 4 is a bottom plan view of the ear ornament used in the construction illustrated in Figures 1, 2 and 3;

Figure 5 is a view taken on the line 5—5 of Figure 2 looking in the direction of the arrows; and

Figure 6 is a side elevational view of the earring construction with the ornament member and the ear clasping member disassembled from each other, and showing a different form of ear ornament member which may be used in the construction.

2

Referring in detail to the figures of the drawing, the earring construction shown in Figures 1 to 5, consists of an ear ornament 1, comprised of a decorative button, of a type used on ladies' wearing apparel, and is formed with a decorative outwardly curved face 2, and an inner flat face 3, having a depressed central portion 4 therein in which is positioned an upwardly projecting shank 5, in the free end of which is formed an eyelet.

The earring is also provided with an ear clasping member of ordinary design but modified in the manner hereinafter described. As shown, the ear clasping member has a U-shaped frame or support 7, the inner arm 8 of which has a bushing 9, provided at the upper end thereof with a threaded opening therethrough to receive a screw member 10. The screw member 10 is formed at one end with a rounded head 11 which is adapted to contact with the ear of the wearer when the earring is being worn. The other end of the screw member is provided with a knurled disc 12, by which the screw is manipulated. On the forward arm of the U-shaped support is secured a circular plate 13 having a depressed portion 14 (see Figure 5) which is presented forwardly of the support. Soldered or otherwise secured to said depressed portion 14, of said plate is one end of a coiled spring 15. The said spring is secured to said plate in such manner that a portion of the end thereof projects as a tongue member across the diameter of the plate as shown in Figure 5, and in detached relation thereto and is bent so that there is formed a hook 17 and a curved free end 18.

The other end of the coiled spring 15 is formed with a conical or tapered portion 19 and so that said tapered portion may be positioned in the depressed portion 4, of the ear ornament shown in Figures 1 to 5, and so that it will be centered around the eye member or eyelet bearing shank 5.

The ear ornament shown in Figure 6, is formed with a flat inner face 22 instead of a concave face, and with an eye member 20 positioned centrally thereof, and with an outer curved face 21.

In assembling the parts of the earring construction shown in Figures 1 to 6, and so that it may be attached to the ear of a wearer thereof, the tapered end 19 of the spring 15 of the ear clasping member is caused to be positioned with respect to the ear ornament 1, and so that it will be seated in the depressed portion 4 thereof and will encircle the eye member 5. The spring is then depressed until the eye member 5 will be positioned adjacent to the end 18 of that part of the spring which is soldered to the circular plate 13. The ear ornament member is then tilted sufficiently so that the eye member 5 thereof will become engaged by the end 18 of the spring and will become locked in the bent up

hook portion 17. The ear ornament will thus be secured to and supported by the ear clasping member and will be resiliently held against the plate 13 thereof by said spring.

With respect to the construction shown in Figure 6, the same procedure is followed in assembling the ear ornament and the ear clasping means except that the tapered portion 19 of the spring 15 is caused to be seated against the flat face 22 of the ear ornament and so that the eye member 20 is centrally positioned in said spring. Then the spring is depressed and the eye member 20 is caused to be engaged by the end 18 and the bent up hook portion 17 of the spring at the point where the spring is attached to the plate 13.

While the ear ornaments illustrated in the drawing and above described, have been referred to as being decorative buttons of the type used on ladies' clothing, we do not wish to be restricted solely to the use of ear ornaments of such type in carrying out the objects of the invention, as it is obvious that any other type of ear ornament having an eye attaching means secured to the rear face thereof may be used in the earring construction of the invention.

It will be seen from the above description that there is provided a novel and exceedingly simple earring construction which may be cheaply manufactured and its parts readily and quickly assembled and securely held in an assembled condition. Also when it is desired to disassemble the parts thereof, it is only necessary to slightly depress the spring of the ear clasping member and then manipulate the ear ornament so as to disengage the eye member thereof from the end 18 of the spring 15. It is also apparent that various different designs of detachable ornamental buttons or other ornamental devices may be used as the ear ornaments and may be resiliently held firmly in position on the ear by the ear clasping means.

What is claimed is:

1. An ear-clip construction of the character described comprising a circular plate for lying against the external surface of a wearer's ear lobe, an ear clasping means carried by said plate to coact with one side thereof for retaining the latter in said position against the ear lobe, a tongue carried by said plate on the other side thereof, said tongue having a hooked mid-portion positioned centrally of the last mentioned plate side for releasably engaging an eye of an ornamental button, and a helical compression spring carried by said plate and positioned to extend from said other plate side with the axis of the spring passing substantially through said hooked mid-portion.

2. The ear clip construction as defined in claim 1 in which said helical spring has a portion adjacent the plate of substantially uniform diametrical turns and terminates in a conical portion.

3. An earring construction of the character described comprising a releasable ear lobe gripping means having a plate and a clasp coacting with one side of said plate for positioning against the external outer and inner surfaces of the ear lobe, respectively, an anchoring hook carried in mid-portion of the other side of said plate, a button-like member having an ornamental front face and a centrally projecting eyelet shank extending from a rear side thereof, said eyelet

shank being releasably engaged with said anchoring hook forming an interconnection between said plate and button-like member, and compression spring means interposed between said plate and shank rear side positioned to exert tension on said interconnection and to maintain the plate and button-like member in parallel relation.

4. An earring construction of the character described comprising a plate for lying against the external surface of an ear lobe of a wearer, an ear clasping device carried by said plate to coact with one side thereof for retaining the plate in said position against the ear lobe, a tongue member carried by said plate on the other side thereof, said tongue having a hooked mid-portion positioned centrally of the last mentioned plate side, a button having an ornamental front face and a shank projecting centrally from a rear face thereof, said shank having an eyelet releasably engaging said tongue hooked mid-portion, and a compression spring interposed between said last mentioned plate side and button rear face to take up slack between the plate and the button.

5. An earring construction of the character described comprising a plate for lying in position against the external surface of an ear lobe of a wearer, ear clamping means carried by said plate to coact with one side thereof for retaining the plate in said position against the ear lobe, a tongue member carried by said plate on the other side thereof, said tongue having a hook mid-portion positioned centrally of the last mentioned plate side, a button having an ornamental front face and a shank projecting centrally from a rear face thereof, said shank having an eyelet releasably engaging said tongue hook mid-portion, and a helical compression spring interposed between said last mentioned plate side and button rear face to maintain the plate and the button in parallel relation.

6. The earring construction, as defined in claim 5, in which the helical spring has a portion adjacent the plate of substantially uniform diametrical turns and terminates in a conical portion engaging the button.

7. In an earring construction of the character described, ear lobe gripping means including a plate, an anchoring hook extending from one side of said plate, and a helical compression spring carried on said side projecting beyond said hook having an axis thereof passing through said hook and an end thereof firmly secured to said plate to exert pressure on a button-like member having an eyelet shank when coupled to said anchoring hook.

8. The earring construction as defined in claim 7 in which the helical compression spring has a portion adjacent the plate of substantially uniform diametrical turns and terminates in a conical portion.
